US0D1046954S

(12) **United States Design Patent** (10) **Patent No.:** **US D1,046,954 S**
(45) **Date of Patent:** **** Oct. 15, 2024**

(54) **SPECTACLE FRAME**

(71) Applicant: **CARL ZEISS VISION INTERNATIONAL GMBH**, Aalen (DE)

(72) Inventor: **Akihiro Muramatsu**, Marugame (JP)

(73) Assignee: **CARL ZEISS VISION INTERNATIONAL GMBH**, Aalen (DE)

(**) Term: **15 Years**

(21) Appl. No.: **29/834,592**

(22) Filed: **Apr. 13, 2022**

Related U.S. Application Data

(62) Division of application No. 35/509,324, filed on Apr. 6, 2020 (U.S. filing date under 35 U.S.C. 384), and having an international filing date of Apr. 6, 2020, now Pat. No. Des. 954,814.

Primary Examiner — Sanjeev Paul

(74) *Attorney, Agent, or Firm* — Shih IP Law Group, PLLC.

(57) **CLAIM**

The ornamental design for spectacle frame as shown and described.

DESCRIPTION

FIG. 1 is a front view of spectacle frame;

FIG. 2 is a rear view thereof;

FIG. 3 is a top view thereof;

FIG. 4 is a bottom view thereof;

FIG. 5 is a left view thereof; and,

FIG. 6 is a perspective view thereof.

The right side view of spectacle frames is omitted because it is a mirror image of the left side view of spectacle frame.

1 Claim, 3 Drawing Sheets
